United States Patent Office

Des. 228,068
Patented Aug. 7, 1973

228,068

BLOWER

Anthony C. Laraia, Torrington, and Jan Najman, Terryville, Conn., assignors to Torin Corporation, Torrington, Conn.

Filed Sept. 20, 1971, Ser. No. 182,306

Term of patent 14 years

Int. Cl. D23—03

U.S. Cl. D23—74

FIG. 1

FIG. 5

FIG. 2

FIG. 3

FIG. 4

FIG. 1 is a perspective view of a blower showing our new design.

FIG. 2 is a left side elevational view thereof on an enlarged scale, the right side being a mirror image.

FIG. 3 is a front elevational view thereof on an enlarged scale.

FIG. 4 is a bottom plan view thereof on an enlarged scale.

FIG. 5 is a top plan view thereof on an enlarged scale.

We claim:

The ornamental design for a blower, as shown and described.
